CLAIM

The ornamental design for a set of inserts for co-culture of cells in microtiter plates, as shown and described.

DESCRIPTION

FIG. 1 is a top, right side perspective view of an embodiment of the invention;

FIG. 2 is a top view thereof;

FIG. 3 is a front view thereof;

FIG. 4 is a bottom view thereof;

FIG. 5 is a left side view thereof;

FIG. 6 is a right side view thereof; and,

FIG. 7 is a back view thereof.
